LIPSTICK CONTAINER

Thomas F. Slater, Waterbury, Conn., assignor to Scovill Manufacturing Company, Waterbury, Conn., a specially chartered corporation of Connecticut

Application October 2, 1956, Serial No. 43,201

Term of patent 7 years

(Cl. D86—10)

Fig. 1

Fig. 1 is a side view of a lipstick container, showing my new design.

Fig. 2 is a top end view, and

Fig. 3 is a bottom end view.

The characteristic features of my design resides in the specific surface ornamental appearance of the two inner bulbous elements which contrast with the outer end portions.

I claim:

The ornamental design for a lipstick container, as shown and described.
